(57) **CLAIM**

The ornamental design for breast cups for a brassiere, as shown and described.

DESCRIPTION

FIG. 1 is a top view of the breast cups for a brassiere according to the present invention; and,

FIG. 2 is an enlarged, side-front perspective view of the breast cups for a brassiere of FIG. 1.

The broken line showing of the brassiere is for illustrative purposes only and forms no part of the claimed design.
